SALT SHAKER

Harry C. Gessler, Brooklyn, N. Y.

Application June 3, 1933, Serial No. 674,131

1 Claim. (Cl. 65—45)

This invention relates to salt shakers or similar dispensing devices.

One object of the invention is to provide a device of the character described having improved means for preventing foreign substances, and especially liquids from dropping into the usual upward opening outlets.

Another object of the invention is to furnish a device of the nature set forth having improved means to facilitate discharge of a pulverulent material.

A further object of the invention is to construct a device of the class alluded to having relatively few and simple parts, preferably none of which is movable in operation, and which parts are easily accessible for inspection and cleaning, and which device is inexpensive to manufacture, neat in appearance, durable, reliable, and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated on the annexed drawing, wherein like parts are designated by the same reference characters throughout the several views.

In the drawing:

Figure 1 is a view in front elevation with parts in section showing a device embodying the invention.

Fig. 2 is an enlarged fragmentary view in inverted position showing the invention in modified form.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

I have observed that salt shakers, especially as used in cafeterias, are frequently unsanitary, as dust and the like enters the outlet openings and settles on the salt shaker in the region of said openings. Sometimes, in handling liquids, such as coffee, a drop thereof falls upon the salt shaker at said openings and tends to produce

a clogging condition of the salt. By this invention, I have endeavored to overcome these conditions.

Referring in detail to the drawing, 10 denotes a dispenser such as a salt shaker embodying the invention. The same may include any container 11 having a discharging means 12. The latter may desirably be embodied in a closure structure which may be in the general nature of a cap, for example, and which may have an annular threaded flange 13 for removable screw engagement with a threaded neck portion 14 of the container.

Extending upward from said flange 13 is a generally frusto-conical tubular element or wall 15 whose smaller end is uppermost. Formed in angularly spaced relation along said wall are a plurality of discharge openings which may include an upper series of openings 16 and a lower series of openings 17. The openings 16 are preferably located in close proximity to the upper end of the conoidal wall 15.

Extending upward from said wall 15 is a generally uniform frusto-conical member 18 of inverted form, aligned with the wall 15, and having its lower end preferably continuously connected with the wall 15 along the circular line 19 defined by the intersecting conoidal surfaces. The diameter of the upper end 20 of the member 18 is sufficiently large to cause the member to substantially overlie the openings 16, 17 in open spaced relation thereabove. The diameter at 20 is generally as great and preferably greater than that of the zone or tubular portion in which the said openings are located, the member 18 being, moreover, located in central relation in said zone and within the series of outlet openings.

A top disc or wall 21 may be connected circumferentially to the wall 18 to form a closed end for the closure means. If desired, said wall 21 may be in the shape of a spherical segment.

Located within the closure means and centrally in the region of the outlet openings, is a downward projecting means which may include an inverted generally conoidal member 22, that may, if desired, have an annular flange 23 extending along the inside of the member 18 for locking member 22 in position. The member 22 is preferably imperforate, and is continuously engaged along a circular line 24 with that part of the closure at the line 19. The member 22 constitutes generally a projection at the elevation of the upper series of openings 16, and extends toward the container 11.

In Fig. 2 is shown a modification 25 of the 110

invention wherein all the parts are the same as in the device 10, except that the conoidal projection 22a has a greater altitude, and may thus extend clear through the region of the outlets 16, 17 and in relative proximity to the neck 14 of the container. The portion 22a may lie in the same plane as the flange 23.

According to the device disclosed herein, the parts 13, 15, 18 and 21 may severally and in different combinations be of one piece construction, and as shown in the drawing they may all be integral. Likewise the parts 22, 23 may be integral with each other. In manufacturing the device, an element is first made consisting of the parts 22, 23 or 22a, 23, said element being then inserted into a suitable tubular structure, which is thereafter spun to form the angle between the members 15 and 16, with said element acting as a backing or reinforcement, and with the flange 20 23 abutting the end wall 21 in a rigid manner.

The manner of operation of the device will now be described. In the normal upright position thereof as shown in Fig. 1, the outlet openings 16, 17 are protected against any foreign solids or liquids dropping thereinto or upon the wall 15, so that the salt or other material to be dispensed is not contaminated, and any clogging due to liquids minimized or wholly prevented. This device is therefore particularly adapted to be used 30 in cafeterias, where the same is handled by a great many people, and oftentimes under crowded circumstances. When a quantity of salt is desired, the shaker is tilted or inverted in the usual manner, the salt S which discharges through the openings 16, 17 passing downward along the conoidal surface of the member 18, which aids in distributing the salt.

The invention has further advantages in resisting clogging of the outlet openings, such as results from absorption of atmospheric moisture by the salt. Thus the members 22 and 22a tend to break up a caked lump of salt, and space the same from the outlet openings. Moreover, these members may form an annular opening with the member 15 to control and cause a gradual movement of the salt toward said outlets, and yet without restricting such movement unduly or creating obstacles or resisting the movement. Furthermore, since the upper series of openings 16 is in relatively close proximity of the members 22, 22a, and particularly the lower ends of said members, in the inverted position, a flow of the fine particles of salt to the outlets is assured, even if there are a considerable number of large caked 55 lumps in the salt shaker.

Due to the angularity of the wall 15, the outlet openings 16 and 17, in the inverted position of the device, present their lower edges to the salt so as to cause an effective dividing or severing action on any caked particles of salt and thus to assure a flow of salt from the device.

It will be appreciated that the angle of each of the members 15, 18 and 22 may, within the scope of the invention, be varied from zero to 180 degrees with the horizontal plane, although the drawing shows preferably an angle of approximately 60 degrees for member 15, an angle of approximately 45 degrees for the member 18, while member 22 is at an angle of approximately 15 degrees, and member 22a at an angle of approximately 45 degrees.

The closure means 12 may be made of any suitable material such as thin sheet metal, which may be plated or otherwise treated to render the same rustproof. There are preferably no movable parts, although this is not of the essence of the invention. The space 26 in the closure is completely closed on all sides, and the parts which may require cleaning are readily accessible.

It will be appreciated that various changes and modifications may be made in the device as shown in the drawing, and that the same is submitted in an illustrative and not in a limiting sense, the scope of the invention being defined in the following claim.

I claim:

In a salt shaker having a container provided with an upper open end, a closure therefor including a tubular element of generally conoidal form and having means at its larger end for connection with the container, said element having its conoidal wall provided with outlet openings, and an inverted conoidal shield having its side wall connected at its smaller end to the upper end of said element in aligned relation therewith, said shield having a closed wall at its upper larger end, said closed wall being permanently connected to the side wall of the shield along an edge of the upper end thereof, said edge being of substantially equal diameter with that of the larger end 115 of the tubular element, the side wall of the shield being substantially straight and the shield overlying the outlet openings and constituting a smooth guide for the full and unobstructed discharge therefrom of salt received thereby from 120 the outlet openings in an inverted position of the salt shaker.

HARRY C. GESSLER.
